ABSTRACT OF THE DISCLOSURE

An improved locking mechanism is disclosed that is used with coin boxes on such devices as automatic washing machines where four smooth tumblers each having a radially extending slot are rotatably secured to a plate forming the closure to the coin box in a recessed manner with the actuating part of the locking structure being spring-biased towards an unlocking condition, the unlocking action being completed through further rotation of the lock tumblers without resort to a separate latch or bolt operator. The tumblers are indexed by forming notches in the edge of a retaining circular flange in the plate and the tumblers are secured against movement while the combination of the lock is changed.

This invention relates to the field of locking devices and more particularly relates to improvements in the closure member or locking cover for a coin box in which there is no bolt operator.

This application is directed to an improvement upon a locking device and relates to co-pending applications filed on Nov. 23, 1966, under Ser. No. 596,489, now U.S. Pat. No. 3,416,537 issued Dec. 19, 1968, entitled "Locking Cover for a Coin Box"; and filed on May 31, 1968, under Ser. No. 733,357 now U.S. Pat. No. 3,473,354 issued Oct. 21, 1969, entitled "Improved Locking Device," and assigned to the same assignee.

Certain types of locks lend themselves to a more convenient means of "picking" and this is especially true where there is no indexing mechanism used so that it is easier for the unscrupulous operator to get a "feel" of the locking mechanism. Where a bolt or latch operator is used with the tumbler mechanisms, the unscrupulous operator may apply pressure to the bolt or latch operator and thus upon manipulation of the tumblers, obtain some feel of the device.

In an attempt to improve the locking structure and overcome the various ways of picking the lock or determining the combination, means have been provided to prevent the operator from obtaining the "feel" of the locking mechanism. Where it is impossible to operate the latch or bolt mechanism, manipulation of the tumblers through gearing and the indexing mechanism tends to alleviate the problem. The indexing mechanism provides a certain amount of "drag" in maneuvering the tumbler mechanisms and in the instant structure, upon the tumblers being set to the proper combination, a spring mechanism is used to urge bolt or latch operator into a position where further manipulation of anyone of the tumblers will open the lock mechanism.

Therefore, it is a general object of the present invention to provide an improved locking mechanism for use with coin-collection equipment of coin-operated mechanisms.

It is another object of the present invention to provide a locking mechanism controlled through a biasing structure and the tumblers of the locking mechanism.

It is a further object of this invention to provide a locking mechanism which is biased towards an open condition and has the latching arms or bolt-biased in an opposite manner and at a greater magnitude.

2

It is still a further object of this invention to provide indexing members and a reduced contact area between the tumblers and pin followers to lessen the possibility of detecting the lock combination.

It is yet another object of the present invention to provide a locking mechanism which may not be opened by brute force.

These and other objects of the invention will more fully appear from the following description, made in connection with the accompanying drawings, wherein like reference characters refer to the same or similar parts throughout the several views, and in which:

FIG. 1 is an elevation view of the front panel of the locking mechanism;

FIG. 2 is a perspective view of a hand tool used to operate the locking mechanism as found in FIG. 1;

FIG. 3 is an elevation view of the rear panel of the locking mechanism shown in a locked condition;

FIG. 4 is an elevation view of the rear panel of the locking mechanism shown in an unlocked condition;

FIG. 5 is a section view of a front plate having a cut-out portion showing the detail of an indexing mechanism as seen taken along lines 5—5 of FIG. 6;

FIG. 6 is a section view taken along lines 6—6 of FIG. 3.

FIG. 7 is a perspective view of a plate member having fingers extending therefrom for use in changing the locking mechanism combination; and

FIG. 8 is a partial section view of the locking arms of the locking mechanism as seen taken along lines 8—8 of FIG. 3.

The locking mechanism as seen from the front and as shown primarily in FIG. 1 discloses a front panel member 30 which has four equally spaced bores 32 through 35 formed therein and which are equally spaced from a centrally located shaft 36 (FIGS. 3 and 6) which is rotatably secured to the rear of the panel and will be described in more detail later. Rotatably situated in each of bores 32 through 35 are four shafts 37 through 40 respectively, the ends of the shafts having a flat portion formed thereon.

The rotation of shafts 37 through 40 is accomplished through the use of a hand tool 41 (FIG. 2) having a shaft engaging end member 42 that corresponds with the flat portion of the shafts so that a rotational movement may be imparted thereto. Concentric with a shaft 43 engaging end member 42, is a circular member 44 which includes indicia around the periphery thereof, specifically displaying twenty-four positions or increments which are fixed positions with respect to shaft rotation.

As seen primarily in FIGS. 3 through 6, shaft 36 has a flanged portion 45 and a shoulder portion 46 with a reduced circular portion 47 extending rearwardly which terminates in a reduced section 49 that is rotatably supported in a bore 50 formed in a back plate member 51. An intermediate plate 52 is secured to plate 30 by suitable means such as four studs 55 through 58 which are threaded to receive four nuts 60 through 63, plate 52 having four holes 64 through 67 formed therein to engage the studs. A third plate member 70 is secured to plates 30 and 52 through the same threaded studs and has its edge portions turned rearwardly to engage and secure plate 51 through suitable means such as machine screws or releasable fasteners. A bore 71 formed in the center of plate 70 supports shoulder 46 of shaft 36 and flange 45 is of a thickness slightly less than that of plate 52, thus rotatably retaining shaft 36. Shafts 37 through 40 also have four flanges 72 through 75 formed therewith which are also secured between plates 30 and 70. Each of flanges 72 through 75 contain a plurality of notches 76 which are equal in number to the indicia on tool 41 and specifically the disk 44 which in the instant case repre-

sents twenty-four different equally spaced radial positions. In other words, each of the notches are separated by 15-degree increments.

The rearwardly extending portion of shaft 37 has a gear 79 secured thereto by a suitable means. Gear 79 mates with another gear 80 which is secured to a shaft 81 by suitable means, the forward end of shaft 81 being rotatably secured in a bore 82 formed in plate 70. A shoulder 83 is formed about shaft 81 immediately to the rear of gear 80 so that gear 80 is secured against axial movement. The rearward portion of shaft 81 terminates in a reduced section 84 which rides in a bore 85 formed in plate 51 to provide rotational movement thereto. A reduced section or annular groove 86 is formed adjacent plate 51 in shaft 81 for reasons which will be set forth in detail subsequently. A tumbler 90 is rotatably fitted about shaft 81 and is appropriately secured to shaft 81 by a set screw 91 which mates with annular groove 86. In other words, tumbler 90 may be rotated with respect to shaft 81 and this will be explained further subsequently.

The additional tumblers and mechanisms are identical to that just described and the details thereof will not be discussed. It will be found that three additional tumblers 95 through 97 are supported by three shafts 100 through 102 respectively. Tumblers 90 and 95 through 97 have four deep slots 104, 105, 106, and 107 respectively formed therein.

A hub 110 is rotatably secured about shaft 36, where the lower portion of hub 110 is in the form of a disc 114. It will be observed that disc 114 and hub 110 may be made integrally or from separate pieces and disc 114 slipped over the square shank of hub 110 and secured thereto by suitable means. Four pins 120 through 123 are secured to camming disc 114 and are shown in a position engaging the edge of the tumblers, slot 104 being in a position to receive pin 220 upon proper alignment of the other tumblers. A spring 124 is secured to one of the edge portions of plate 70 by suitable means such as a lug 125 which has a hole 126 formed therein with spring 124 being anchored thereto. The other end of spring 124 is secured to disc 114 by suitable means such as a machine screw 127. Spring 124 is anchored to disc 114 in such a manner that pins 120 through 123 are urged into engagement with tumblers 90 and 95 through 97. Spring 124 has only a slight tension placed upon disc 114 and is sufficient to cause all of pins 120 through 123 to slip into the corresponding slots of the tumblers when all of the slots are properly aligned.

To aid in preventing someone from obtaining the "feel" of the lock tumbler positions, an indexing mechanism is shown in FIG. 5 wherein a pair of spring members 134 and 135 are secured in a substantially square recess or cutout portion 136 of plate 52. Recess 136 contains a pair of shoulder members 137 and 138 which support spring member 134 at the ends thereof and an inward projecting finger 140 communicates with the center portion of spring member 134 which is bent around finger 140. Spring member 134 has a pair of detent portions 141 and 142 formed therein midway between shoulders 137, 138, and finger member 140 respectively whereby detent portions 141 and 142 engage the indentations or notches 76 formed in flanges 72 and 75 respectively. Thus as flange 72 is rotated, a portion of the "feel" is transferred through spring member 134 to the adjacent flange 75 so that the position of tumbler 90 with respect to pin 120 is somewhat obscured by communication of detent 142 with flange member 75. In a similar manner, a pair of shoulders 144 and 145 cooperate with a finger member 146 to produce tension in spring member 135 and in particular at a pair of detent portions 147 and 148 respectively. It will be noted that the shoulder members 137, 138, 144, and 145 along with the cooperating finger members 140 and 146 set the proper tension of spring members 134 and 135 with respect to flanges 72, 75, 74 and 76.

The lock mechanism also includes a pair of substantially right-angle arms 156 and 157 which are pivotally secured in place over studs 58 and 56. As seen in FIG. 8, arms 156 and 157 are bent at appropriate places to provide the proper clearances and emerge through the rearwardly extending portions of plate 70. Secured to ends of arms 156 and 157 at a location greatest from studs 58 and 56 are a pair of upturned members 158 and 159 respectively. Upturned portions 158 and 159 engage a pair of edge portions 160 and 161 of camming disc 114 when it is rotated to draw arms 156 and 157 inwardly towards hub 110. A spring member 162, in the form of a wire spring, is secured to upstanding arm portions 158 and 159 to urge arms 156 and 157 away from hub 110 towards a locked condition. That is, spring 162 keeps arms 156 and 157 in a locked condition at all times until cam 114 is rotated where edges 160 and 161 pick up the upturned portions and cam them towards hub 110. Springs 162 has a tension which is greater than spring members 124 to insure that the lock will only be opened upon arriving at the proper combination and upon further rotation of one of tumblers 90 or 95 through 97. Thus spring 124 causes pin 120 through 123 to move only partially in the corresponding slots and the lock mechanism must be opened by a rotation of one of the tumblers.

Because it is desirable to change the combination of the lock and to insure that the tumblers do not rotate while the combination is being changed, a flat plate number 174 (FIG. 7) has four pins or fingers 175 through 178 secured therein which pass through holes formed in backplate 51 (not shown) to engage the four deep slots 104 through 107 respectively. In other words, pins 175 through 178 are placed in slots 104 through 107 as shown in FIG. 3, which lock the tumblers in place. The set screws 91 are then loosened and hand tool 41 is used to set the combination for any ppropriate number that the operator desires after which set screws 91 are again tightened.

The front panel member 30 may be formed from material such as case-hardened steel as well as the shafts which are exposed to the front of the panel. By the use of the extremely hard materials at the face of the lock mechanism, it will be seen that it is impossible to apply any "brute force" to the lock mechanism because rotation of any of the shafts which are coupled to the tumblers merely causes the tumblers to rotate through the driving mechanism of the gears and as the pins pass over the slots, there is no "feel" transmitted to the shafts. In fact, it may be found desirable to chamfer or bevel the edges of slots 104 through 107 where desirable. Additionally, pins 120 through 123 may be formed with a slight taper away from disc 114 so that only a small area is involved between the engagement of the tumblers and the pins. Under such circumstances, the smaller the contact area between the tumblers and pins on disc 114, the less chance there is of any "feel" being transmitted through the locking mechanism, and especially where the spring indexing mechanism is used, such as found in FIG. 5. In fact, it has been found that the lock mechanism has a very light "touch" and if shafts 37 through 40 are not turned in the proper direction after reaching the position where all of the pins are aligned with their corresponding slots, the lock will again be turned to a position which is not the proper combination and the tumblers will again have to be aligned.

What is claimed is:

1. A locking mechanism for a coin box having a lock portion secured thereto comprising:
  - (a) plate means having a plurality of bores formed therein and adapted to close the coin box;
  - (b) lock means rotatably secured to the rear of said plate means including a plurality of pin means;
  - (c) arm means movably secured to the rear of said plate means in engaging relationship with said lock means and adapted to move towards and away from

- said lock means in cooperation with the lock portion of the coin box;
- (d) spring bias means secured between said plate means and said locking means urging said lock means towards an unlocking rotation; and
- (e) a plurality of rotatable tumbler means secured to said plate means and extending through said plurality of bores, the rear portions thereof having a smooth circular edge and a radially oriented slot extending therefrom, said rear portions cooperatively engaging said pin means, said spring bias means facilitating partial rotation of said lock means upon all of said pin means engaging said slots, and further rotation of any of said tumbler means completing rotation of said lock means.
2. The structure set forth in claim 1 including:
- (f) first gear means rotatably mounted in said plurality of bores and extending to the front and rear of said plate means; and
- (g) second gear means secured to said tumbler means and meshing with said first gear means in driven relationship.
3. The structure of claim 2 including:
- (h) hand tool means adapted to engage and rotate said first gear means from the front of said plate means; and
- (i) indicia means including first indicia secured to said hand tool means in circular form and second indicia secured to said plate means adjacent said bores.
4. The structure of claim 2 including:
- (j) tumbler-engaging means having a plurality of finger members engaging all of said tumbler means against rotation simultaneously at rotational positions of said tumbler means representative of a predetermined setting; and
- (k) releasable securing means releasably securing said second gear means to said tumbler means.
5. The structure set forth in claim 4 including:
- (l) a back plate spatially disposed behind said plate means and connected thereto, said back plate rotatably supporting said second gear and tumbler means and having a plurality of holes formed therein for receiving said finger members of said tumbler-engaging means.
6. The structure set forth in claim 1 including:
- (m) indexing means including flange members with peripheral notches formed therein equal in number to the predetermined number of rotational rest positions of said tumbler means secured to said tumbler means and having spring members with detents formed therein operatively engaging at least two of said flange members simultaneously to cooperate

with said notches formed therein, said spring members adapted to be secured to said plate means.

7. The structure set forth in claim 1 including:
- (n) indexing means having a plurality of first elements thereof formed in said plate means and a plurality of second elements formed in said plurality of rotatable tumbler means, said first and second elements cooperating to arrest rotation of said tumbler means at predetermined angular positions with respect to said plate means.
8. The structure set forth in claim 7 wherein one of said elements is in the form of indentations formed therein and the other of said elements is in the form of a detent operatively cooperating with said indentations.
9. The structure set forth in claim 8 wherein said plate means and rotatable tumbler means include:
- (o) a least a pair of plates secured to each other in flat relationship having a recess formed in at least one of said plates disposed to encompass each of said bores; and
- (p) a circular flange member fixedly secured to said tumbler means and rotatably secured in said recess preventing axial movement with respect to said pair of plates.
10. The structure set forth in claim 1 including:
- (q) second spring bias means connected to said arm means urging said arm means towards a locked condition having a higher spring constant than, and in opposition to, said spring bias means secured between said plate means and said lock means.
11. The structure set forth in claim 1 wherein said pin means are tapered and engage said tumbler means over a limited portion of the length of said pin means.
12. The structure set forth in claim 1 including:
- (r) a camming disc secured to said lock means and having said pin means secured thereto, said camming disc imparting a concentric rotation to said arm means when said lock means is rotated.
